FIG. 1

FIG. 2

FIG. 3

FIG. 5 BY *Adrian Medent* ATTORNEY.

UNITED STATES PATENT OFFICE

2,310,106

MASSAGING APPARATUS

Jesse G. Miller, Tiffin, Ohio

Application November 18, 1940, Serial No. 366,136

4 Claims. (Cl. 128—58)

This invention relates to a new and improved massaging apparatus and more particularly to apparatus especially suitable for massaging the spinal column and adjacent back portions of the human anatomy.

In treating or massaging the spinal column and portions of the human back associated therewith, it is highly desirable that the massaging action takes place progressively in one direction only along the spinal column, preferably from the base of the neck to the sacrum. In addition, the massaging action or pressure applied upon the body should be substantially uniform throughout the area treated, and during the period of treatment. The body should also be substantially relaxed during treatment and therefore the maximum benefit is not obtained from a treatment if the patient actively participates in effecting the treatment. Although, heretofore, various types of devices have been provided and used for massaging purposes, such devices have not been particularly well suited for treating the human back and spinal column. The outstanding drawbacks of such prior devices have been their inability to effect a uniform massaging action upon that part of the anatomy under treatment, and the use of such devices required that the patient take an active part in the application of the treatment. Such devices as were particularly developed for spinal massaging, attempted to treat the entire back at one time by means of a plurality of massaging elements which contacted localized portions of the anatomy, or employed an oscillating movement of the massaging elements which defeated the purpose of the treatment or proved harmful to the patient.

By the present invention there is provided a new and improved device for massaging the spinal column and adjacent portions of the anatomy which substantially overcomes the aforementioned defects and disadvantageous features of prior devices. The apparatus is adapted to apply a uniform massaging action progressively along the entire length of the spinal column in one direction from the base of the neck to the sacrum; may have the vigor of its action adjusted to suit the constitution of the patient; and operates entirely without supervision or effort on the part of a patient being treated.

These and other objects of the invention will be better understood from the following detailed description, taken in conjunction with the accompanying drawing wherein there is illustrated a preferred form of the invention, and wherein:

Figure 1 is a side elevational view of a new and improved massage table constructed in accordance with the invention;

Figure 2 is a top sectional view taken on line 2—2 of Figure 1;

Figure 3 is a fragmentary top plan view taken on line 3—3 of Figure 1;

Figure 4 is a sectional view taken on line 4—4 of Figure 2; and

Figure 5 is an enlarged fragmentary sectional view taken on line 5—5 of Figure 2.

With reference to the drawing, and to Figure 1 in particular, wherein there is illustrated a preferred embodiment of the invention, the numeral 10 broadly indicates a table-like support having a top 11 suitably supported on leg members 10a. The top 11 through which extends a substantially rectangular longitudinal opening 12, is preferably of such length as to accommodate a patient in a prostrate position thereon, and the opening 12 is of sufficient width and length to coincide with the spinal area of the average patient's back from the base of the neck to the sacrum. A flexible covering 13 is extended over the opening 12, and serves to prevent the body of a patient from coming in direct contact with any moving part of the massage unit.

The massage unit is mounted beneath the top of the table in alignment with the opening 12 and includes a frame consisting of longitudinal side members 14 and cross members 15. The side members 14 are formed with their upper edge surfaces 16 contoured to simulate the curvature of a normal human spine. Journaled in the longitudinal frame members 14 adjacent the ends thereof, are transversely extending shafts 18, the ends of which are extended beyond the frame members 14 to receive the sprocket wheels 19. One of the shafts 18 is further extended and has mounted thereon a pulley wheel 20 which receives a belt 21a. Endless chains 21 connect the sprocket wheels disposed on respective sides of the frame and serve to support and move massaging rolls 22 in a predetermined path.

The rolls 22 are mounted on shafts 23 suspended between the endless chains 21. The rolls are preferably made with wooden cores 24 to which there is bonded a tire 25 of a resilient material such as sponge rubber constituting the massaging surface of the roll. On each side of a massaging roll and rotatably mounted on the shafts 23 are rollers 26 so spaced as to contact and ride upon the upper edge surfaces 16 of the longitudinal frame members 14. As the chains 21 are moved by the sprocket wheels 19, the massaging

rolls 22 carried thereby are moved in a path defined by the contour of the upper edge surfaces of the side frame members and as they pass over the upper edge surfaces of those members, the path of travel simulates the curvature of the normal human spine. The massage unit is so positioned with respect to the top of the table as to allow the rolls 22 to project through the opening 12 and contact the anatomy of a person lying on the table 10.

The adjusting mechanism for raising and lowering the massage unit with respect to the top surface of the support 10 shown and described herein, has been found to be especially satisfactory in that it may be easily operated by a patient disposed on the top of the table without its being necessary for the patient to leave the apparatus or change his position.

The massage unit is suitably supported on a U-shaped frame 30 by means of blocks 31 extending between the frame and the side members 14 of the massage unit. The open end of the frame 30 is pivotally supported to the leg members 10a by means of bolts 32. The free end of the frame is adapted to rest in its lowermost position upon blocks 32a secured to the side of the supporting table. For raising and lowering the massage unit the end member 33 of the frame 30 is attached to the ends of cables 38 depending from the raising and lowering mechanism. This mechanism comprises spaced cross beams 34 secured to the table 10 and supporting therebetween pulleys 35. A screw shaft 36 is journaled in suitable bearings also carried by the cross beams. Mounted on the screw shaft 36 is a nut 37, to which the ends of cables 38 are attached. Movement of the nut 37 in either direction along the shaft is effected by rotation of the screw shaft 36, by means of handle 39 mounted on the side of the table and operatively associated with the shaft 36.

The power unit for driving the endless chains 21 includes a reversible motor 40 mounted on a platform 42 supported adjacent one end of the table 10. The motor through a gear reduction unit 41 and pulley 43 is adapted to drive the belt 21a which engages the pulley 20.

In using the device the patient is positioned on the supporting surface 11, so that his spinal column will be resting on the loose covering over the opening 12 in the top of the table 10. The position of the massage unit is then adjusted so that the periphery of a massaging roll extends through the opening 12 sufficiently to exert the desired massaging effect on the patient's back. As the massaging rolls are moved across the opening 12 they follow a path similar to the curvature of a normal human spine, and thereby effect a uniform massaging pressure on the anatomy of the patient disposed on the table. The massaging rolls are caused to travel preferably from the head of the device toward the foot of the device. However, the direction of travel may be reversed if necessary to suit the requirements of the patient being treated. Other adjustments may be made to increase the benefits of the apparatus for a particular patient by varying the pressure exerted by the massaging rolls through the use of the raising and lowering mechanism as has already been described, and by varying the speed of the rolls and consequent vigor of the massaging action, which is accomplished by corresponding adjustments in the speed of the electric motor which drives the massage unit.

Having thus described my invention so that those skilled in the art may be able to understand and practice the same, what I desire to obtain by Letters Patent is defined in the appended claims.

5 I claim:

1. In a massaging device of the class described a supporting surface having an opening therethrough, a frame member supported below said opening and having spaced upper edge surfaces contoured to simulate the curvature of the spinal portion of the human body, a massaging roll rotatably mounted on a shaft extending between and supported on the edge surfaces of said frame member and having a portion of the periphery thereof adapted to project through the opening in the supporting surface, and means for moving said shaft along the upper edge surfaces of the frame member whereby the periphery of the roll is caused to travel along said opening in a path simulating the contour of a normal human spine.
- 10 2. A massaging apparatus comprising a table-like frame, a body-supporting top thereon with an opening therethrough, a frame having spaced upper supporting surfaces contoured to simulate the spinal portion of the human body mounted for vertical movement beneath said opening, a massaging roll movably supported by said frame surfaces and adapted to have a portion of the periphery thereof projecting through said opening, and means for moving said massaging roll in a predetermined path along the upper surface of said frame and in one direction across said opening.
- 15 3. In a massaging device of the class described a supporting surface having an opening therethrough, a frame member supported below said opening and having spaced upper edge surfaces contoured to simulate the curvature of the spinal portion of a human body, massaging rolls rotatably mounted on shafts extending between endless chains and supported on the upper edge surfaces of said frame member, said massaging rolls adapted to have a portion of the peripheral surfaces thereof extending through the opening in the supporting surface, means for moving said massaging rolls along the upper edge surfaces of the frame member whereby said rolls are caused to travel in a predetermined path, and means for varying the speed and direction of travel of said rolls.
- 20 4. In a massaging device of the class described a supporting surface having an opening therethrough, a yieldable covering disposed over said opening, a frame member supported below said opening and having spaced upper edge surfaces contoured to simulate the curvature of a normal human spine, a plurality of massaging rolls rotatably mounted on shafts extending between and supported on the edge surfaces of said frame member, a portion of the periphery of each of said massaging rolls adapted to project through the opening in the supporting surface, and means for moving said shafts along the upper edge surfaces of the frame member whereby the periphery of each of the massaging rolls is caused to travel in a path parallel to the upper surface of the frame member, said means serving to move the rolls across the said opening in such a manner that only one roll at a time contacts a body disposed on the supporting surface of the device.

JESSE G. MILLER.
